Attorney, Agent, or Firm—Perman & Green, LLP*[57] **CLAIM**

The ornamental design of a rear housing portion of a telephone handset, as shown and described.

DESCRIPTION

FIG. 1 is a rear plan view showing my new design;

FIG. 2 is a top, rear and left side perspective view thereof;
and,

FIG. 3 is a top, rear and right side perspective view thereof.
The broken lines showing of the telephone handset is for
illustrative purposes only and forms no part of the claimed
design.
